CONTAINER

Harold L. De Lisle, Two Rivers, Wis.

Application November 16, 1935, Serial No. 50,074

14 Claims. (Cl. 129—26)

These improvements relate to containers which are more customarily in the form of drawers insertable into a cabinet and designed to hold such sheet material as tracings, blueprints, etc. used in drafting rooms. Such sheet material is usually of large size and the filing and handling of such material for ready reference with a minimum of difficulty and without injury to the sheets is a matter of importance.

10 A principal object of the present invention is to provide unitary means for storing the sheets in flat condition and for elevating certain of the uppermost sheets for access to sheets lower in the stack, the uppermost sheets being held and 15 clamped in elevated position when desired.

In some aspects the present invention is a specific improvement on the devices of my prior Patents No. 1,746,610 issued June 17, 1930, and No. 1,924,109 issued August 29, 1933.

20 The present invention will be readily understood by reference to the accompanying drawings in which—

25 Figure 1 is a plan view showing the major part of an illustrative container associated with a cabinet or the like, a portion of which is shown in section, parts being broken away for convenience;

30 Figure 2 is a longitudinal section of the structure taken along the line 2—2 of Fig. 1 with the parts in normal position;

35 Figure 3 is a view similar to Fig. 2 but with the parts in alternative position; and

Figure 4 is an enlarged fragmentary detail view.

35 In the illustrative construction shown in the drawings the container is shown in the form of a drawer 10 adapted to slide horizontally on runners 11 within the cabinet 12, the container being shown in Fig. 1 in outermost or open position, it being understood that the drawer and parts of the cabinet not shown are of conventional construction, and need not be shown. Both the drawer and cabinet are desirably of sheet metal construction for strength and for fire resistance, 40 and the drawer has a flat bottom 13 upon which are stacked the separate flat-lying sheets 14. The drawer shown has a front wall 15 and parallel side walls 16 extending longitudinally.

45 The side walls 16 are desirably spaced apart a substantially greater distance than the width of the sheets 14 so that the sheets are received between inner walls 17 each spaced a suitably short distance laterally inwardly of its adjacent outer wall 16.

55 The space between each pair of walls 16, 17

therefore provides a channel 17a in which is received one of the pairs of links and levers for elevating certain of the sheets, the sheets being thus protected from contact with the mechanism along the edges of the sheets where they are particularly susceptible to be torn or frayed.

5 A cover element 18 in this instance in the form of a partial closure for the drawer is carried, as here shown, medially longitudinally of the container on one side of a pair of levers 19, each of 10 which is pivoted to the container as at 20 in one of the channels 17a, brackets 21 being secured therein for this purpose. The cover member 18 therefore spans the sheets and since it terminates short of the front and rear of the drawer the 15 sheets extend both rearwardly and forwardly beyond this cover member. Thus the forward portions of the sheets may be raised and folded back over the cover member 18 to provide access to sheets lower in the stack. In this instance 20 also I have shown an auxiliary cover member 22 in the form of a section hinged as at 23 to the main cover member 18, the section 22 extending almost to the front wall of the container and near this point having hand-gripping means such 25 as the opening 24 therein for readily raising it. In order that the cover section 22 may follow the sheets downwardly regardless of the number of sheets in the stack, this section terminates laterally short of the inner side walls 17 permitting 30 it to rest on the bottom 13 when there are no sheets in the container. Thus the forward portions of the sheets are normally prevented from curling upwardly and being damaged thereby. The inner side walls 17 are also desirably cut out 35 as at 25 to permit the main cover element 18 to be received therein in closer proximity to the sheets in the vicinity of the forward edge of the member 18.

When access is desired to, say, a sheet 26 lying 40 some way down in the stack of sheets 14, the cover section 22 is first folded back over the cover member 18 and the sheets 27 normally uppermost of the sheet 26 are then also folded back over both the section 22 and the cover member 45 18. The cover member 18 may then be swung upwardly on its pivots 20, leaving the sheet 26 exposed over the greater part of its area so that it may be readily removed and returned to the drawer in its proper place without removing the 50 sheets 27 entirely from the drawer.

55 My present improved unitary device includes means next described for maintaining the sheets 27 in elevated position and temporarily clamping them in that position so that the hands of the 55

operator may be entirely free for handling the sheet 26.

In the present embodiment such means includes a pair of bar links 28, each of which is 5 flexibly secured to the container in one of the channels 17a. In this instance, as best shown in Fig. 4, a link 28 has at its forward end a trunnion pin 29 which may be rigidly secured to the link and which extends laterally on each 10 side thereof, one end of this trunnion pin being received in a slot 30 or other runway in the channel 17a. The slots 30 as here shown may be formed in a bearing block 31 secured to the inner face of the outer wall 16. Thus the forward end of the link has somewhat in the nature 15 of a lost-motion connection with the drawer, for enhanced flexibility. The other end of the trunnion pin 29 which is not received in the slot 30 may be extended toward the inner wall 17 to guide the pin in the slot and prevent casual 20 displacement from the slot by abutment with the inner wall 17 upon tendency to displace the pin from the slot. The upper end of each of the links 28 is also slotted as at 32 and receives 25 therein a headed stud 33 or other pivot member secured to the cover levers or pivoted supports 19.

In accordance with my invention also, the links 28 are extended rearwardly as at 34 beyond the rearmost ends of the slots 32 and thus 30 beyond the cover elements when elevated and desirably when in slightly rearwardly inclined position as shown in Fig. 3. To these rearward extensions 34 of the links 28 are secured, transversely of the container, a clamping member such 35 as the cylindrical rod 35. Thus when the cover elements are raised as shown in Fig. 3 with the sheets 27 folded thereover, the free ends of the sheets are frictionally engaged between the cover elements and this bar 35, and so are prevented 40 from being casually displaced from this elevated position by the weight of the sheets themselves or by other accidental means. The inner walls 17 are desirably notched as at 36 to receive the rod 35 when in lowered position as shown in 45 Figs. 1 and 2.

When access to the sheets has been completed, the cover element may be dropped forwardly, releasing the sheets from the clamping means and causing them to fall back into position in the 50 drawer with the cover elements 18 and 22 overlying them to hold them smoothly flat. Thereupon the entire drawer may be pushed rearwardly into the cabinet to restore it to storing position.

It will be apparent that when the cover element 18 is dropped forwardly from the open 55 position shown in Fig. 3, it will move the links 28 forwardly relative to the slots 30 while at the same time permitting the links to drop with element 18 toward the horizontal. At the same time or at least when the links 28 reach the end 60 of their forward movement relatively to the slots 30, the studs 33 on the levers 19 will move forwardly in the elongated slots 32 of the links 28, 65 thus moving the cover element 18 away from the clamping rod 35 and releasing the sheets 27. The distance between the notch 36 and the forward end of the slot 30 is just sufficient to permit the rod 35 to be received in the notch 36 when 70 the trunnion pin 29 abuts the forward end of the slot.

Such changes may be made as fall within the scope of the appended claims without departing from the invention.

Having described my invention, I claim:

1. A container of the character described for holding loose sheets in a stack, a cover member pivoted to the container at each side thereof medially from front to rear and having a main portion terminating short of the front of the 5 container whereby the forward portions of the sheets may be folded back thereover, and elevated with the cover upon movement upwardly of the cover on its pivot, a pair of links flexibly connected to the container and the cover to support the cover in position inclined slightly rearwardly of the vertical, and a rod carried by the links parallel with the cover and disposed immediately rearwardly of the cover in its rearwardly inclined position, whereby the said folded back 15 forward portions of the sheets are frictionally engaged by the rod when the cover is in said rearwardly inclined position.

2. The structure of claim 1 wherein the cover comprises a main portion and a section flexibly 20 connected with said main portion, said section being adapted to cover the said forward portions of the sheets when in flat condition and to be folded back therewith between the main portion and the rod.

3. The structure of claim 1 wherein the cover comprises a main portion and a section flexibly 25 connected with said main portion, said section being adapted to cover the said forward portions of the sheets when in flat condition and to be 30 folded back therewith between the main portion and the rod, and wherein the cover members are of sheet metal.

4. The structure of claim 1 wherein the cover comprises a main portion and a section flexibly 35 connected with said main portion, said section being adapted to cover the said forward portions of the sheets when in flat condition and to be 40 folded back therewith between the main portion and the rod, and wherein the said section has hand-gripping means thereon.

5. The structure of claim 1 wherein the links are slotted and the cover carries headed studs movable in said slots.

6. The structure of claim 1 wherein the links 45 are each flexibly connected to the container on a movable pivot for limited movement longitudinally of the container.

7. The structure of claim 1 wherein the links are slotted and the cover carries studs movable 50 in said slots, and wherein the links are each flexibly connected to the container on a movable pivot for limited movement longitudinally of the container.

8. The structure of claim 1 wherein the container is a drawer of sheet metal and has channels 55 therein at each side thereof from front to rear, the links being secured in said channels whereby the sheets are guarded therefrom.

9. The structure of claim 1 wherein the container is a drawer of sheet metal and has channels 60 therein at each side thereof from front to rear, the links being secured in said channels whereby the sheets are guarded therefrom, and wherein the drawer contains a slotted block in 65 each channel and the links carry pins secured fast thereto and movable in the slots in the blocks, and wherein one of the walls of each channel cooperates to hold the pins of the links in said slots.

10. In a structure of the class described a drawer of sheet metal having channels therein at each side thereof from front to rear, links being flexibly secured in said channels, a main cover member pivoted to said links and to the drawer 70

apart from the links, the inner wall of each channel being cut out downwardly to receive the links and said cover member, and an auxiliary cover member flexibly connected to the main cover member and terminating transversely of the container short of said inner walls.

5 11. The structure of claim 1 wherein the links are flexibly connected to the container forwardly of the points where the cover is pivoted to the container.

10 12. A container of the character described for holding loose sheets in a stack, a cover member mounted in the container and pivoted thereto at each side only of the container and adapted to swing toward and away from the sheets, said member terminating short of the front and rear of the container whereby the forward portions of the sheets may be folded back thereover and elevated therewith, a pair of links flexibly connecting the member and container, and clamping means carried jointly by the member and links for en-

gaging the portions of the sheets folded over the member.

13. In a container of the character described for holding loose sheets in a stack, the combination of a cover member rotatable in the container, and upon which the sheets are adapted to be folded back, supporting means carried by the container for the cover member, and means carried by the container for clamping the sheets to the cover member, actuated into and out of operation by relative movement of the cover member and support.

14. The structure of claim 13 wherein the supporting means is in the form of two links having a lost motion connection with both the container and the cover member and the clamping means includes a transverse rod carried by free ends of the links and between which and the cover member the sheets are held.

HAROLD L. DE LISLE.
